SELECTOR FOR AUTOMATIC PHONOGRAFS

Mahlon W. Kenney, Oak Park, and Herman G. Jensen, Chicago, Ill., assignors to J. P. Seeburg Corporation, Chicago, Ill., a corporation of Illinois

Application November 4, 1944, Serial No. 561,986

21 Claims. (Cl. 177—353)

This invention relates to selectors for automatic phonographs in which one or more recordings can be selected for playing seriatim.

In our copending application Ser. No. 505,776, filed October 11, 1943, we have described and claimed a selector adapted to be operated to select a recording by means of two series of impulses. Thus with one hundred selecting bars the first train of impulses determines the decade and the second train of impulses determines the unit for any desired recording. The recordings and selector elements corresponding thereto may conveniently be numbered 00 to 99. The selector may be operated by means of a dial which is adapted, when operated in the usual manner to transmit a train of impulses, the number depending upon the number dialed. To prevent accidental selection, it is preferred to transmit three impulses when the number 0 is dialed, four impulses when the number 1 is dialed and so forth. The selector comprises a selector arm which is adapted to cooperate with any of the one hundred selector elements which are arranged in an arc. Each of the first train of impulses moves the actuator through ten spaces of the selector elements. Each of the second train of impulses moves the actuator one spacing between the selector elements. The arrangement is such that two trains of three impulses bring the actuator to the first selector element. This results from dialing 00. If the number 99 is dialed the actuator is brought into alignment with the last selector element and if any intermediate number is dialed the actuator is brought into alignment with the corresponding selector element.

In the selector of the application referred to the units impulses control the actuation of an electromagnetic relay which step the actuator one spacing on each energization. Each decade impulse must control the movement of the actuator through ten spaces. Each decade impulse controls an escapement which permitted the structure carrying the actuator to move through these ten spacings under the influence of a spring. On reset the spring was tensioned by a motor.

In order to prevent accidental selection by two series of accidental impulses the selector elements were arranged in an arc and the actuator could not be brought into alignment with any selector element unless the two accidental trains comprised four decade impulses and at least one units impulse or three decade impulses and at least three units impulses. The electromagnetic means responsive to the two trains of impulses is arranged to respond only to trains of impulses having a fairly critical timing and the chance of four or three accidental impulses occurring in proper timed relation is infinitesimally small and in practice is absolutely zero.

One of the objects of the present invention is to provide a greatly simplified selector of this general type in which the stepping of the actuator by both decades and units impulses is effected by simple electromagnetic means such as a solenoid or relay thus avoiding the necessity of a motor and simplifying and reducing the time of the reset operation.

A further object of the invention is to provide a selector of this general type in which the means for actuating the actuator to displace a selector element is maintained inoperative until the decade train of at least the minimum number of impulses is received.

A further object of the invention is to provide a selector of this general type in which the means for actuating the actuator to displace a selector element is maintained inoperative until a units train of at least the minimum number of impulses is received.

It may here be noted that these two features, or either of them enables the selector elements to be located around a complete circle.

A further object of the invention is to provide improved means for returning the selector to zero or normal condition in the event that only a decade train, accidental or otherwise is received by the selector.

A further object of the invention is to provide a modification in which the selector automatically resets itself after a decade train only is received and actuates one of the selector elements to control the playing of one recording.

Other objects, advantages, and capabilities of the invention will appear from the following description of preferred embodiments thereof, taken in conjunction with the accompanying drawings in which,

Fig. 1 is an elevational view, partly in section of the selector and associated phonograph elements;

Fig. 2 is an inverted plan view, part of the framework being broken away;

Fig. 3 is an elevational view of the decade stepper and associated elements as viewed on the line 3—3 of Fig. 2;

Fig. 4 is an inverted plan detail showing elements associated with the decade stepper, part shown in Fig. 2 being omitted for the sake of clarity;

Fig. 5 is an elevational sectional detail view taken on the line 5—5 of Fig. 2 and showing the reset relay and associated elements;

Fig. 6 is an inverted plan detail view taken on the line 6—6 of Fig. 5;

Fig. 7 is an inverted plan detail sectional view

taken on the line 7—7 of Fig. 5, certain elements being omitted for the sake of clarity;

Fig. 8 is a perspective view of elements associated with the unit stepper, as viewed from the under side;

Fig. 9 is an inverted plan detail view taken on the line 8—8 of Fig. 1;

Fig. 10 is a detail view as viewed in Fig. 1 parts being omitted to show the switch assembly;

Fig. 11 is an inverted plan detail view taken on the line 11—11 of Fig. 10;

Fig. 12 is a wiring diagram, and

Fig. 13 is a fragmentary wiring diagram illustrating a modification.

Referring to the drawings reference numerals 15 20 indicate selector bars each of which individually corresponds to a recording on the phonograph. In the embodiments illustrated there are 100 bars 20. Upward displacement of any bar 20 as viewed in Fig. 1 results in putting the phonograph into operation to reproduce the corresponding recording. Any number of the bars 20 may be displaced upwardly with the result that the phonograph plays all the corresponding recordings. The bars 20 are mounted in a stationary frame 21 which includes parallel plates 22, 23, and 24 provided with aligned openings through which the bars 20 may move longitudinally. Each bar is provided notches 25 and 26 which are engaged by a resilient annulus 27 which may suitably be a ring of relatively weak coiled spring. The coiled spring 27 is confined between the annular plate 24 and a parallel annular plate 28 which may suitably be of insulating material. The plates 22, 23, 28, and 24 are held in assembly relation by means of bolts 29 and associated spacers 30. When the bars 20 are in their normal position the spring 27 engages the notches 26. When a bar 20 is moved upwardly the spring 27 seats in its notch 25 so that the bar is held in upwardly displaced position until it is pushed down.

The bars 20 may be associated with a phonograph of the type referred to in the application mentioned above. Each bar 20 is grounded and when it is displaced upwardly the projection 31 carried by each bar engages an insulated ring 32. The ring 32 is connected to the phonograph motor 33, which is connected to a source of power such as the secondary of transformer 34, the other end of the secondary being grounded. It will thus be seen that when any bar 20 is displaced upwardly to selecting position the phonograph motor 33 is put into operation. A switch 35 arranged in parallel with the contacts 31 and 32 is arranged to be closed by the motor 33 after it is put into operation. This switch is arranged to be opened momentarily during the next record changing cycle of the phonograph so that if no bar 20 is up at that time the phonograph motor 33 ceases to operate. When the motor 33 is put into operation it tends to drive a shaft assembly 36 through at least a complete revolution. The assembly 36 carries a projection 37 which is arranged to engage the upper end of an actuated bar 20. The drive of the shaft 36 from the motor 33 is frictional so that the assembly 36 is arrested by engagement of its projection 37 with the actuated bar. The position of the shaft assembly 36 determines the recording to be played which recording, of course, corresponds to the arresting bar 20. After the selection has been thus determined a plunger 38 is automatically actuated to press the arresting bar 20 back to normal position. This occurs after the switch 35 closes so that the

phonograph motor 33 continues to operate until the corresponding recording has been completely reproduced. Thereupon the phonograph goes into its record changing cycle and in this cycle the switch 35 is opened. If no other bar 20 is in actuated position the phonograph motor stops. If any other bar or bars 20 is or are in actuated position the motor 33 continues to operate until all the corresponding recordings have been reproduced, whereupon the opening of the switch 35 finally terminates the operation of the phonograph.

The bars 20 are pushed upwardly by an actuator arm 39 which is pivotally mounted at 40 on a table 41. This table is rigidly secured to a shaft 42 in axial alignment with the center of the circular series of bars 20. The table 41 carries guide means 43 which accurately locate the outer end of the arm 39 so that it registers with the bars 20. The arm 39 is biased downwardly by a spring 44. The arm 39 carries an armature 45 which is arranged to be attracted by an electromagnet 46 mounted on the plate 23. The armature 45 is preferably in the form of a disc so that the arm 39 may be moved upwardly with equal force by the magnet 46 irrespective of the direction in which the bar 39 is located. The insulating ring 47 carries a metal contact ring 48 which is adapted to be engaged by the resilient contact arm 49 when the arm 39 is moved upwardly. The contacts 47 and 48 constitute the switch 49 hereinafter referred to.

The shaft 42 is rotatably supported in suitable bearings in a sub-frame 50, which is part of the frame 21. The sub-frame 50 supports the decade 35 relay 51, the units relay 52 and the reset relay 53 which control the various positions of the arm 39.

The decade relay 51 is a solenoid which actuates a bar 54 moving it to the right as viewed in Fig. 2 each time the relay 51 is energized. The bar 54 is biased towards the left as viewed in Figs. 1 and 2 by means of a spring 55 which abuts against a washer 56 at the end of the bar and against a guide bracket 57 mounted on the sub-frame 50. The bar 54 carries rack teeth 58 which mesh with the teeth of a pinion 59 mounted on the shaft 42 for free rotation. Consequently, each time the relay 51 is energized the gear 59 rotates part of a revolution in the clockwise direction as viewed from above (counter-clockwise as viewed in Figs. 2 and 4) and then returns to initial position owing to the action of the spring 55. The bar 54 carries a contact 60 which engages an insulated contact 61 each time the relay 51 is energized. The contacts 60 and 61 constitute a switch 62 hereinafter referred to. The shaft 42 is biased in the counter-clockwise direction as viewed from above (clockwise direction as viewed in Fig. 2) by means of a spring 63 one end of which is anchored to the sub-frame 50, the other end being secured to a disc 64 rigidly mounted on the shaft 42. A stop 65 depending from the table 41 is arranged to engage a pin 66 projecting upwardly from an arm 67 freely mounted on the shaft 42 above the sub-frame 50. The arm 67 is arranged to engage stops 68 and 69 projecting upwardly from the sub-frame 50. When the reset relay 53 is energized the dogs holding the shaft 42 away from normal position are disengaged in manner hereinafter described with the result that the spring 63 rotates the shaft 42 in counter-clockwise direction as viewed from above (clockwise as viewed in Figs. 2 and 4) until the pin 65 engages the pin 66 and carries the arm 67 around until it engages the rigid pin 69, which thus determines the initial or

zero position of the actuator 39. A weak coil spring 70 connected to the arm 67 and to the sub-frame 50 causes the arm to follow the stop 65 as the table 41 moves away from its zero position until the arm engages the stop 89.

The disc 64 carries an upwardly directed pin 70 which is arranged to engage an arm 71 extending radially from a disc 72 freely mounted on the shaft 42. The arm 71 is arranged to engage the depending end of a lever 73 pivotally mounted on the sub-frame 50. The sub-frame 50 carries stops 74 for the lever 73. The lever 73 controls the switches 75 and 76. In the zero position of the actuator 39 the pin 70 is in engagement with the arm 71 which in turn is in engagement with the lever 73 so that the switch 75 is open and the switch 76 is closed. These switches are constituted by three poles 77, 78, and 79. The pole 79 is biased towards the poles 77 and 78. The pole 77 is biased more strongly towards the pole 79. In the zero position of the actuator 39 the lever 73 holds the pole 71 away from the pole 79 so that the switch 75 is open and the switch 76 is closed. When the pin 70 is moved away from the arm 71 by the first actuation of the decade relay the switch 75 is closed and immediately thereafter the pole 71 moves the pole 79 away from the pole 78 so that the switch 76 is open, a condition shown in Fig. 11. These switches retain this condition until the reset relay 53 is energized to permit the shaft 42 and actuator 39 to return to normal position, when the switch 76 closes and immediately thereafter the switch 75 opens. A normally open switch 183 is associated with the switch 75 to close simultaneously with the switch 75.

The reset relay 53 is a solenoid whose armature 80 is biased outwardly by a spring 81. The armature 80 is connected to a bar 82. When the reset relay is energized the bar 82 moves to the right as viewed in Figs. 5 and 7 and a spring biased latch 83 locks the armature in. The latch 83 is pivotally supported on a bracket 84 carried by a bracket 87 on the sub-frame 50. The bar 82 carries a pin 85 which projects upwardly through an opening in the transverse portion of an inverted U-shaped lever 86. The lever 86 is pivotally mounted at intermediate positions of its legs on the bracket 87 carried by the sub-frame 50. The ends of the U-shaped lever 86 engage shoulders 88 on a horizontal slider 89. The slider is mounted on a horizontal part of the bracket 87 by means of headed screws 89 which extend through slots 92 in the slider 89. A spring 93 connected to the slider 89 and to an element rigid with the sub-frame 50 biases the shoulders 88 of the slider 89 against the depending ends of the U-shaped lever 86. It will be readily seen in Fig. 5 that when the reset relay 53 is energized or when its armature is locked in the U-shaped lever 86 is in its dotted line position in Fig. 5 and the slider 89 is projected to the left as viewed in Figs. 5 and 6. When it is thus projected into the dotted line position of Fig. 6 it engages a roller 94 on the tail of a dog 95. The dog 95 is pivotally mounted on a toothed segment 96 and the dog 95 is biased by a spring 97 towards engagement with a ratchet wheel 98. The spacing of the teeth on the ratchet wheel 98 is 36° so that each tooth space corresponds to a ten step movement of the actuator 39. The ratchet wheel 98 is rigidly mounted on the shaft 42. The sector 96 is loose on the shaft and is biased by a spring 99 towards its normal position shown in Fig. 2 which is defined by en-

gagement of a stop 100 on the sector with the sub-frame 50. The inner end of the slider 89 Fig. 6 is of accurate formation so that it is effective to engage the roller 94 and disengage the dog 95 from the ratchet wheel 98 in any position in which the sector 96 may be located during operation.

The armature 101 of the units relay 52 is arranged to engage the sector 96 and move it one tooth at a time in the clockwise direction as viewed from above (counter-clockwise as viewed in Fig. 2). The tooth spacing on the sector 96 corresponds to the angular relation between the bars 20 so that energization of the units relay 52 effects movement of the actuator 39 from a position beneath one bar 20 to a position beneath the next bar 20. When the units relay 52 is operating the teeth of the sector 96 are engaged by a dog 102. In the normal or zero condition of the device the dog 102 is latched out by a latch member 103 which is pivotally mounted on the sub-frame 50 and is arranged to engage a shoulder 104 on the dog 102. A spring 105 biases the dog 102 towards the teeth of the sector 96 and a spring 106 biases the latch 103 towards latching position. A rod 107 on the armature of the relay 52 is arranged to engage a pin 108 on the latch 103 in such manner that when the units relay is energized the dog 103 is moved to unlatching position. Consequently, the first units impulse unlatches the dog 102 so that the sector 96 is held against return movement during receipt of the units impulses.

The slider 89 carries a downwardly projecting pin 109 which is arranged to engage the upturned end 110 on the tail of the dog 102. Consequently, when the reset relay 53 is energized and the slider 89 is moved to the left as viewed in Figs. 5 and 6 the pin 109 moves the tail of the dog 102 away from the teeth of the sector 96 at the same time that the slider disengages the dog 95 from the ratchet wheel 98. Consequently, the shaft 42 and the actuator 39 are freed and are returned to their normal position by the spring 63. The armature of the reset relay is locked in by the latch 83 so that the dogs 95 and 102 are held in inoperative position until they are released by the first actuation of the decade relay 51 and the first actuation of the units relay 52, respectively.

The pinion 59 which is oscillated by the decade relay is provided with an upwardly directed projection 111 (Figs. 5 and 7) which is arranged to engage the latch 83 allowing the bar 82 to move outwardly. This movement swings the U-shaped lever 86 so as to move the slider 89 from its dotted position in Fig. 6 to its full line position in that figure. This movement permits the dog 95 to engage operatively the ratchet wheel 98 as shown in full lines in that figure. The pinion 59 is provided with a downwardly directed projection 112 which is adapted to engage the upturned end 113 of an arm 114 freely mounted on the shaft 42. The arm 114 is biased in the counter-clockwise direction as viewed from above (clockwise as viewed in Figs. 2 and 4) by means of a spring 115. The engagement of the upturned end 113 with the projection of 112 serves as a stop for the arm 114. A dog 116 pivotally mounted on the arm 114 is arranged to cooperate with the ratchet wheel 98. The dog is biased towards the ratchet wheel by means of a spring 117 but is normally held out of engagement with the ratchet wheel 98 by engagement of a stop 118 carried by the dog 116 and arranged to cooperate with a sta-

tionary guide member 119. It will readily be seen in Fig. 2 that when the decade relay 51 is energized the arm 114 is swung around in the counter-clockwise direction, as viewed in that figure and the stop 118 runs off the guide member 119 so that the point of the dog 116 moves towards the ratchet wheel 98 and carries it one tooth in the counter-clockwise direction (clockwise as viewed from above). The final position of the dog 116 is shown in dotted lines in Fig. 4. It is to be noted that the dog in this final position engages an abutment 120 which limits the movement of the dog and the ratchet wheel to one tooth.

A switch 121 is associated with the armature 101 of the units relay 52 so that this switch is closed during each units impulse.

As the actuator arm 39 is stepped around the arm 67 follows the stop 65 until the arm 67 strikes the stop 69 on the sub-frame 50. The arm 67 rigidly carries a spring contact arm 124 which normally engages the larger of two segments 125 and 126 which are mounted on a piece of insulation 127 carried by the sub-frame 50. The segments 125 and 126 are separated by a small gap and are connected in a manner herein-after described. It may here be noted that if the actuator 39 is moved 33 spaces of the bars 20 from initial position the contact arm 124 engages the segment 126. A larger displacement of the actuator 39 leaves the contact arm 124 in engagement with the segment 125 because the arm 67 ceases to follow the actuator arm when it engages the stop 69. The contact arm 124 is initially in engagement with the segment 125 and it remains in such engagement if the actuator 39 is displaced 32 or less spacings of the bars 20 from its initial position.

A bell crank lever 128 is pivotally mounted on the sub-frame 50, one end of the lever extending above the sector 96 for a distance equivalent to almost three toothed spaces on the sector. The lever 128 holds a switch 129 open and a switch 130 closed. The lever 128 is normally held out of engagement with the sector 96 by its engagement with a cam surface 131 on the dog 102, this cam surface being arranged to engage the lever 128 when the dog is moved to latched out position. When the dog 102 is unlatched by the first actuation of the units relay 52 the cam surface 131 is moved away from the lever 128 so that this lever is forced against the upper side of the sector 96 by the leaves of the switches 129 and 130. On the third units impulse the sector 96 clears the end of the lever 128 so that switch 130 opens and switch 129 closes. The switches remain in this condition until the reset relay 53 is again energized whereupon the cam surface 131 on the dog 102, in moving to unlatched position, engages the lever 128 opening switch 129 and closing switch 130 and bringing the other end of the lever above the normal position of the sector 96 which returns to its normal position as a result of the disengagement of the sector teeth by the dog 102.

The selector is energized by a transformer 132. The secondary 133 provides heater current for the tubes 134, 135 and 136. The tubes 135 and 136 are gas tetrodes and may suitably be 2051 tubes. Their anodes are connected to the ends of the secondary 137, the center tap of which is connected to the pole 19 common to the two switches 75 and 76.

The secondary 138 has its opposite ends con-

nected to the anodes of a full wave rectifier tube 139. The center tap of the secondary 138 is connected to line 140. The cathode of the tube 139 is heated by a secondary 141. The cathode is connected through a choke coil 142 to a line 143. Opposite ends of the choke coil 142 are connected through condensers 144 to the line 140 to establish a filter. The conductors 143 and 140 are grounded through resistors 145 and 146 which may suitably have values of 4,800 ohms and 1,200 ohms. The resistor 146 is a voltage divider the arm of which is connected to the line 147. The power supply is arranged to provide 250 volts positive on the line 143 and about minus 34 volts on line 147.

The secondary 148 is connected to the reset relay 53 and to one side of the normally open switch 149. The other side of the reset relay 53 is connected to the ungrounded side of the switch 149 and to one side of a normally open switch 150. Switches 149, 150 and a normally open switch 184 are controlled by a relay 151. The other side of the switch 149 is connected to one side of the electromagnet 46, the other side of which is connected to one side of the normally open switch 128. The other side of the switch 150 is connected to the segment 125 and to one side of the normally closed switch 130. The other side of the switch 128 is connected to the segment 126. The other side of the switch 130 and the contact arm 124 are grounded.

One side of the relay 151 is connected to the line 147 and to a condenser 152 which may suitably be a two microfarad condenser. The condenser 152 is connected to the common pole of the normally closed switch 153 and the normally open switch 154. The other side of the switch 153 is connected to the other side of the relay 151 and the other side of the switch 154 is connected through a limiting resistor 155, suitably of 100 ohms, to the line 143. It will readily be understood that when switch 154 is closed the condenser 152 is charged and that when the switch 153 is closed the condenser 152 is discharged through the relay 151, momentarily closing switches 148, 150 and 184. A condenser 156 has one side connected to one side of the normally open switch 157, to the common pole of the normally closed switch 158 and normally open switch 159 and to one side of the switch 184. The other side of the condenser 156 is connected to one side of the switch 183, the other side of which is grounded. The other side of the switch 184 is connected to the line 143. The line 147 is connected through a limiting resistor 160, which may suitably be 100 ohms to the other side of the switch 157. The line 143 is connected to the other side of the switch 159, to one side of a transfer relay 161 and to one side of a relay 162. The other side of the relay 161 is connected to the ungrounded side of the switch 62 and the other side of the relay 162 is connected to the ungrounded side of the switch 112. The relay 161 is a slow release relay which remains energized when the decade relay 51 is receiving a series of impulses, repeatedly closing the switch 62. The relay 162 is also a slow release relay which remains energized when the units relay 52 is receiving a series of impulses, repeatedly closing the switch 112. Consequently, during the reception of decade impulses a normally open switch 163 is closed, normally closed switch 158 is opened, normally open switch 159 is closed, a normally closed switch 164 is opened and normally open switch 165 is closed. The common pole of the

switches 164 and 165 is connected to the pole 71 of the switch 75. The other side of the switch 164 is connected to the ungrounded side of the relay 52. The other side of the switch 165 is connected to the pole 78 of the switch 76 and to the ungrounded side of the relay 51. The other side of the switch 158 is connected through a resistor 166 which may suitably be a ten megohm resistor, to a line 167. One side of the switch 163 is also connected to the line 167. The other side of the switch 163 is connected to a line 168. The line 168 is connected through a resistor 169 which may be a 33,000 ohm resistor to the line 141. The line 168 is connected to the ungrounded side of a condenser 170 which may be a ten microfarad condenser. The resistor 169 and the condenser 170 constitute a filter for removing the ripple from the bias voltage supplied to the tubes 135 and 136. The line 168 is also connected to one side of a normally open switch 171, the other side of which is connected to the line 167. The line 168 is connected to the line 167 by a limiting resistor 172, which may be a 100 ohm resistor, and a five megohm resistor 173. A one microfarad condenser 174 is connected across the resistor 173.

The switches 153, 154, 171 and 157 are controlled by the slow release relay 162. Consequently, when units impulses are being received by the relay 52 switch 153 is open and switches 154, 171 and 157 are closed. At the termination of the units impulses the switches resume their normal condition.

The line 167 is connected through a 150,000 ohm resistor 175 to a line 176 which is connected through 120,000 ohm resistors 177 and 178 to the control grids of the tubes 135 and 136. The cathodes and screen grids of these tubes are grounded. The line 176 is connected to the ungrounded side of a switch 179 which is actuated by a dial 180. This dial is arranged so that if 0 is dialed the switch 179 closes three times, if 1 is dialed the switch 179 closes four times and so on. It is to be understood that any other signaling means for effectually increasing the grid bias of the tubes 135 and 136 for a desired number of times may be employed instead of the dial 180 and switch 179. This result can be accomplished by means of radio frequency impulses supplied to the radio frequency transformer 181. The secondary of the transformer 181 is connected to the anodes of the rectifying tube 134 which may be a 6H6 tube. The rectified current is filtered by the filter 182 and the rectified positive voltage is applied to the line 176.

Normally the voltage on the grids of the tubes 135 and 136 is about minus thirty volts. When the switch 179 is closed the grid voltage is increased above the flash point of the tubes, which is about minus seven volts. Likewise when an impulse of radio frequency is applied to the tube 134 the voltage of the grids increases so as to cause the tubes 135 and 136 to flash. Each time the tubes 135 and 136 flash direct current is supplied to the common pole 79 of the switches 75 and 76. Normally the selector is actuated by two trains of impulses, the first train being the decade impulses and the second train being the units impulses. The first decade impulse is supplied to the decade relay 51 through the switch 76. The first decade impulse consequently closes the switch 62 energizing the relay 161 and closing the switch 165. The first energization of the relay 51 effects a

movement of the shaft 42 through an angular distance corresponding to ten spaces of the bars 20 and results in the closing of the switch 75 and the opening of the switch 76. Consequently, the second and subsequent decade impulses are supplied to the decade relay 51 through closed switches 75 and 165. When the decade impulses terminate the switch 62 remains open and the relay 161 is deenergized. The switch 165 opens and the switch 164 closes. During the first decade impulse the switch 163 is closed discharging the condenser 174 and providing a direct connection between the line 168 and 167. Consequently at the end of the first and the succeeding decade impulses the grids of the tubes 135 and 136 immediately attain their normal bias and the impulses supplied to the decade relay 51 are properly terminated. During the decade impulses the condenser 156 becomes charged.

The next train of impulses, the units train are supplied to the units relay 52 through the closed switches 75 and 164. This train repeatedly closes the switch 112 and maintains the relay 162 energized. The timely receipt of the first units impulse discharges the condenser 156 through the resistor 160 and closed switch 161. During the receipt of the first units impulse and during the reception of the subsequent units impulses the condenser 174 and resistor 173 are shunted by the switch 171 so that the flashes of the tubes 135 and 136 are correctly terminated. During the reception of the units impulses the switch 154 is closed and the condenser 152 is charged. At the termination of the units impulses the switch 153 is closed and the condenser 152 is discharged through the relay 151 closing the switches 169 and 150. If the selector has been thus actuated by two trains of at least the minimum number of impulses, that is three or more impulses in each train the contact 126 is grounded, the switch 180 is opened and the switch 129 is closed. Consequently, the circuit of the electromagnet 46 is completed by the closing of the switch 149 and the bar 20 corresponding to the two trains is displaced. Energization of the electromagnet 46 closes the switch 49 energizing the relay 53 so that the mechanical part of the selector is returned to zero or normal condition leaving the selected bar 20 displaced.

During the decade impulses the condenser 156 is charged through the closed switch 159. At the termination of the decade impulses the condenser 156 discharges slowly through switch 158, resistor 166 and R. C. circuit 173, 176. This circuit is a time delay circuit in which the condenser 174 is slowly charged up until the voltage on the line 167 builds up to cause the tubes 135 and 136 to flash. As a result of this flash a single impulse is transmitted through switch 75 and switch 164 to the relay 52 displacing the sector 96 one tooth momentarily closing switch 112. The relay 162 is energized once. The condenser 152 is charged and is immediately discharged through the relay 151. The switch 129 is open and the switch 180 is closed because three units impulses were not received. The circuit of the reset relay 53 is completed through the momentarily closed switch 150 and the closed switch 180 so that the selector is returned to normal or zero condition. Since the switch 129 is open the electromagnet 46 is not energized and no bar 20 is displaced. Thus if the operator dials merely one train and does not dial a second train, the selector is cleared

and put into condition for the reception of a properly dialed section. Likewise if the decade relay 51 is actuated one or more times accidentally by surges received by the transformer 181, the selector is brought to zero or normal condition by the single pulse automatically provided by the discharge of the condenser 156 through the time delay circuit 173, 174. The period of time elapsing before the generation of the automatic pulse is controlled by the values of the elements 173 and 174 and the associated elements in the circuit. The specific values given are intended for a three second period and are particularly adapted for a device which automatically transmits two trains. Such an impulse transmitter is described and claimed in the copending application Ser. No. 561,984, filed November 4, 1944. This period can however be greatly increased for use with a dial, such as the dial 180 to provide a greater permissible time between the consecutive operation of the dial to transmit a complete selecting signal.

A short accidental surge on the line may close the switch 82 without displacing the actuator 88 or opening switches 76 or closing switch 183. In this event the condenser 156 is not charged because its charging circuit is open at switch 183. But if the accidental surge is sufficiently long the actuator 88 may be moved and the switch 76 may be opened and switch 183 closed. The energization of the relay 161 closes the switch 186, charging the condenser 156. The discharge of the condenser causes the tubes 135 and 136 to flash supplying an impulse to the relay 82 with the result that the relays 162 and 151 and the reset relay 53 are energized so that the actuator 88 is returned to normal position and switch 76 is closed and switch 183 is opened. Each time the relay 161 is energized, that is after the relay 82 has received a units series of impulses or after it has received an automatic impulse, the switch 183 is closed and the switch 184 is momentarily closed so that the condenser 156 is charged. Normally the reset relay 53 is energized so that the actuator 88 returns to its normal position and the switch 183 is opened breaking the discharge circuit of the condenser 156. But if the reset relay fails to operate sufficiently due to momentary low voltage on the power line or other cause the switch 183 remains closed and the condenser 156 is discharged until the voltage on the line 187 is raised to create another automatic units impulse which does result in the effective energization of the reset relay 53. This operation may be visualized by holding the armature of the reset relay, and dialling a decade series of impulses. The relay 161 becomes energized repeatedly at time intervals depending upon the constants of the R. C. circuit.

In the case of a coin controlled phonograph, in which the operation of the dial 180 is permitted when a coin is inserted, it is undesirable to clear the selector if the patron fails to dial the second train without reproducing a recording. In this case the dial is arranged to transmit four impulses when the number 0 is dialed and a greater number of impulses when any other number is dialed. The switches 128 and 130 and the lever 128 are omitted. As shown in Fig. 13 the electromagnet 46 is connected directly to the segment 128. A dialed decade signal carries the arm 124 over to the segment 126. In this case the automatic impulse closes the switch 148 and energizes the electromagnet

48 so that a bar 20 is actuated. The electromagnet 46 closes the switch 49 energizing the reset relay 53 so that the selector is returned to zero condition. The possibility of four or more accidental impulses in properly timed relation to energize the decade relay 51 four or more times like a regular train of decade impulses is infinitely small and in practice is zero. One, two or three accidental impulses in properly timed relation leaves the contact 124 on the sector 125. The automatic units pulse closes the switch 150 and the reset relay 53 is energized, its circuit being completed through sector 125 and grounded contact 124. No bar 20 is actuated in this case because the circuit of the electromagnet 46 is not complete.

Although the invention has been described in connection with the specific details of preferred embodiments thereof, it must be understood that such details are not intended to be limitative of the invention except in so far as set forth in the accompanying claims.

We claim:

1. A selector for automatic phonographs comprising a series of displaceable selector members each corresponding to an individual recording, an actuator arranged to be brought into alignment with any one of said displaceable selector members, electromagnetic means 25 for operating said actuator to displace a selector member in alignment therewith, a pair of stepping means adapted to respond to impulses to step said actuator into alignment with said selector members, one of said stepping means 30 being adapted to move said actuator through large steps and the other stepping means being adapted to move said actuator through small steps, impulse supply means normally connected to one stepping means, means controlled by last mentioned stepping means for connecting said impulse supply means to the other stepping means, means controlled by the other stepping means for energizing said electromagnetic means, and means associated with one of said stepping means to prevent the energization of said electromagnetic means except when last mentioned stepping means has received a definite minimum plurality of impulses.

2. A selector for automatic phonographs comprising a series of displaceable selector members each corresponding to an individual recording, an actuator arranged to be brought into alignment with any one of said displaceable selector members, electromagnetic means for operating said actuator to displace a selector member in alignment therewith, a pair of stepping means adapted to respond to impulses to step said actuator into alignment with said selector members, one of said stepping means being adapted to move said actuator through large steps and the other stepping means being adapted to move said actuator through small steps, impulse supply means normally connected to one stepping means, means controlled by last mentioned stepping means for connecting said impulse supply means to the other stepping means, means controlled by the other stepping means for energizing said electromagnetic means, and means associated with both said stepping means to prevent the energization of said electromagnetic means except when each stepping means has received a definite minimum plurality of impulses.

3. A selector for automatic phonographs comprising a circumferential series of equally spaced

displaceable selector members each corresponding to an individual recording, an actuator arranged to be brought into alignment with any one of said displaceable selector members, electromagnetic means for operating said actuator to displace a selector member in alignment therewith, a pair of stepping means adapted to respond to impulses to step said actuator into alignment with said selector members, one of said stepping means being adapted to move said actuator through large steps and the other stepping means being adapted to move said actuator through small steps, impulse supply means normally connected to one stepping means, means controlled by last mentioned stepping means for connecting said impulse supply means to the other stepping means, means controlled by the other stepping means for energizing said electromagnetic means, and means associated with one of said stepping means to prevent the energization of said electromagnetic means except when last mentioned stepping means has received a definite minimum plurality of impulses.

4. A selector for automatic phonographs comprising a circumferential series of equally spaced displaceable selector members each corresponding to an individual recording, an actuator arranged to be brought into alignment with any one of said displaceable selector members, electromagnetic means for operating said actuator to displace a selector member in alignment therewith, a pair of stepping means adapted to respond to impulses to step said actuator into alignment with said selector members, one of said stepping means being adapted to move said actuator through large steps and the other stepping means being adapted to move said actuator through small steps, impulse supply means normally connected to one stepping means, means controlled by last mentioned stepping means for connecting said impulse supply means to the other stepping means, means controlled by the other stepping means for energizing said electromagnetic means, and means associated with both said stepping means to prevent the energization of said electromagnetic means except when each mentioned stepping means has received a definite minimum plurality of impulses.

5. A selector for automatic phonographs comprising a series of displaceable selector members each corresponding to an individual recording, an actuator arranged to be brought into alignment with any one of said displaceable selector members, electromagnetic means for operating said actuator to displace a selector member in alignment therewith, a pair of stepping means adapted to respond to impulses to step said actuator into alignment with said selector members, one of said stepping means being adapted to move said actuator through large steps and the other stepping means being adapted to move said actuator through small steps, impulse supply means normally connected to one stepping means, means controlled by last mentioned stepping means for connecting said impulse supply means to the other stepping means, switch means controlled by the last mentioned stepping means for energizing said electromagnetic means, and switch means associated with one of said stepping means operable after last mentioned stepping means has received a definite minimum plurality of impulses to permit energization of said electromagnetic means.

6. A selector for automatic phonographs com-

prising a series of displaceable selector members each corresponding to an individual recording, an actuator arranged to be brought into alignment with any one of said displaceable selector members, electromagnetic means for operating said actuator to displace a selector member in alignment therewith, a pair of stepping means adapted to respond to impulses to step said actuator into alignment with said selector members, one of said stepping means being adapted to move said actuator through large steps and the other stepping means being adapted to move said actuator through small steps, impulse supply means normally connected to one stepping means, means controlled by last mentioned stepping means for connecting said impulse supply means to the other stepping means, switch means controlled by the last mentioned stepping means for energizing said electromagnetic means, and switch means associated with each of said stepping means operable after each mentioned stepping means has received a definite minimum plurality of impulses to permit energization of said electromagnetic means.

7. A selector for automatic phonographs comprising a circumferential series of equally spaced displaceable selector members each corresponding to an individual recording, an actuator arranged to be brought into alignment with any one of said displaceable selector members, electromagnetic means for operating said actuator to displace a selector member in alignment therewith, a pair of stepping means adapted to respond to impulses to step said actuator into alignment with said selector members, one of said stepping means being adapted to move said actuator through large steps and the other stepping means being adapted to move said actuator through small steps, impulse supply means normally connected to one stepping means, means controlled by last mentioned stepping means for connecting said impulse supply means to the other stepping means, a switch controlled by the other stepping means for energizing said electromagnetic means, and a switch in series with said switch and said electromagnetic means arranged to be closed by one of said stepping means when actuated for a definite minimum plurality of times.

8. A selector for automatic phonographs comprising a circumferential series of equally spaced displaceable selector members each corresponding to an individual recording, an actuator arranged to be brought into alignment with any one of said displaceable selector members, electromagnetic means for operating said actuator to displace a selector member in alignment therewith, a pair of stepping means adapted to respond to impulses to step said actuator into alignment with said selector members, one of said stepping means being adapted to move said actuator through large steps and the other stepping means being adapted to move said actuator through small steps, impulse supply means normally connected to one stepping means, means controlled by last mentioned stepping means for connecting said impulse supply means to the other stepping means, a switch controlled by the other stepping means for energizing said electromagnetic means, and a pair of switches in series with said switch and said electromagnetic means, each of said pair of switches being associated with one of the stepping means so as to be closed after the stepping means has been actuated a definite plurality of times.

9. A selector for automatic phonographs com-

prising a series of displaceable selector members each corresponding to an individual recording, an actuator arranged to be brought into alignment with any one of said displaceable selector members, electromagnetic means for operating said actuator to displace a selector member in alignment therewith, a pair of stepping means adapted to respond to impulses to step said actuator into alignment with any of said selector members, one of said stepping means being adapted to move said actuator through large steps and the other stepping means being adapted to move said actuator through small steps, impulse supply means normally connected to one stepping means, means controlled by last mentioned stepping means for connecting said impulse supply means to the other stepping means, means controlled by the other stepping means for energizing said electromagnetic means, and time delay means controlled by the stepping means normally connected to the impulse supply means for automatically supplying an impulse to the impulse supply means in the event that a second series of impulses is not supplied to said impulse supply means within a predetermined time.

10. A selector for automatic phonographs comprising a series of displaceable selector members each corresponding to an individual recording, an actuator arranged to be brought into alignment with any one of said displaceable selector members, electromagnetic means for operating said actuator to displace a selector member in alignment therewith, a pair of stepping means adapted to respond to impulses to step said actuator into alignment with any of said selector members, one of said stepping means being adapted to move said actuator through large steps and the other stepping means being adapted to move said actuator through small steps, impulse supply means normally connected to one stepping means, means controlled by last mentioned stepping means for connecting said impulse supply means to the other stepping means, means controlled by the other stepping means for energizing said electromagnetic means, time delay means controlled by the stepping means normally connected to the impulse supply means for automatically supplying an impulse to the impulse supply means in the event that a second series of impulses is not supplied to said impulse supply means within a predetermined time, and means controlled by the other stepping means for rendering said time delay means inoperative.

11. A selector for automatic phonographs comprising a series of displaceable selector members each corresponding to an individual recording, an actuator arranged to be brought into alignment with any one of said displaceable selector members, means biassing said actuator to an initial position, electromagnetic means for operating said actuator in any of its positions to displace a selector member in alignment therewith, a pair of stepping means adapted to respond to impulses to step said actuator into alignment with any of said selector members, one of said stepping means being adapted to move said actuator through large steps and the other stepping means being adapted to move said actuator through small steps, impulse supply means normally connected to one stepping means, means controlled by last mentioned stepping means for connecting said impulse supply means to the other stepping means, means controlled by the other stepping means for energizing said electromagnetic means, and means controlled by said other stepping means for releasing said

actuator for automatic return to its initial position by said biassing means.

12. A selector for automatic phonographs comprising a series of displaceable selector members each corresponding to an individual recording, an actuator arranged to be brought into alignment with any one of said displaceable selector members, means biassing said actuator to an initial position, electromagnetic means for operating said actuator in any of its positions to displace a selector member in alignment therewith, a pair of stepping means adapted to respond to impulses to step said actuator into alignment with any of said selector members, one of said stepping means being adapted to move said actuator through large steps and the other stepping means being adapted to move said actuator through small steps, impulse supply means normally connected to one stepping means, means controlled by last mentioned stepping means for connecting said impulse supply means to the other stepping means, means controlled by the other stepping means for energizing said electromagnetic means, means associated with one of said stepping means to prevent the energization of said electromagnetic means except when last mentioned stepping means has received a definite plurality of impulses, and means controlled by said other stepping means for releasing said actuator for automatic return to its initial position by said biassing means.
13. A selector for automatic phonographs comprising a series of displaceable selector members each corresponding to an individual recording, an actuator arranged to be brought into alignment with any one of said displaceable selector members, means biassing said actuator to an initial position, electromagnetic means for operating said actuator in any of its positions to displace a selector member in alignment therewith, a pair of stepping means adapted to respond to impulses to step said actuator into alignment with any of said selector members, one of said stepping means being adapted to move said actuator through large steps and the other stepping means being adapted to move said actuator through small steps, impulse supply means normally connected to one stepping means, means controlled by last mentioned stepping means for connecting said impulse supply means to the other stepping means, means controlled by the other stepping means for energizing said electromagnetic means, and means associated with each stepping means to prevent the energization of said electromagnetic means except when each mentioned stepping means has received a definite minimum plurality of impulses.
14. A selector for automatic phonographs comprising a series of displaceable selector members each corresponding to an individual recording, an actuator arranged to be brought into alignment with any one of said displaceable selector members, means biassing said actuator to an initial position, electromagnetic means for operating said actuator in any of its positions to displace a selector member in alignment therewith, a pair of stepping means adapted to respond to impulses to step said actuator into alignment with any of said selector members, one of said stepping means being adapted to move said actuator through large steps and the other stepping means being adapted to move said actuator through small steps, impulse supply means normally connected to one stepping means, means controlled by last mentioned stepping means for connecting said impulse supply means to the other stepping means, means controlled by the other stepping means for energizing said electromagnetic means, and means controlled by the other stepping means for energizing

said electromagnetic means, time delay means controlled by the stepping means normally connected to the impulse supply means for automatically supplying an impulse to the impulse supply means in the event that a second series of impulses is not supplied to said impulse supply means within a predetermined time, and means controlled by said other stepping means for releasing said actuator for automatic return to its initial position by said biasing means.

15. A selector for automatic phonographs comprising a circumferential series of displaceable selector members each corresponding to an individual recording, an actuator arranged to be brought into alignment with any one of said displaceable selector members, means biasing said actuator to an initial position, electromagnetic means for operating said actuator in any of its positions to displace a selector member in alignment therewith, a pair of stepping means adapted to respond to impulses to step said actuator into alignment with any of said selector members, one of said stepping means being adapted to move said actuator through large steps and the other stepping means being adapted to move said actuator through small steps, impulse supply means normally connected to one stepping means, means controlled by last mentioned stepping means for connecting said impulse supply means to the other stepping means, means controlled by the other stepping means for energizing said electromagnetic means, means associated with one of said stepping means to prevent the energization of said electromagnetic means except when last mentioned stepping means has received a definite number of impulses, time delay means controlled by the stepping means normally connected to the impulse supply means for automatically supplying an impulse to the impulse supply means in the event that a second series of impulses is not supplied to said impulse supply means within a predetermined time, means controlled by said other stepping means for rendering said time delay means inoperative, and means controlled by said other stepping means for releasing said actuator for automatic return to its initial position by said biasing means.

16. A selector for automatic phonographs comprising a selector member adapted to be stepped to a selecting position, a movable structure carrying said selector member, a second movable structure, a dog arranged operatively to connect said movable members, a stepper adapted to move the first movable member through steps of definite size, a second stepper for moving the second movable member and thereby the first movable member through steps of a different size, a second dog adapted to prevent return movement of the second movable member, a latch for holding the second dog away from the second movable member, means normally supplying impulses to the first stepper, means controlled by the first stepper for connecting the impulse supply means to the second stepper, a reset relay, means controlled by the first stepper for rendering the first dog operative, means controlled by the second stepper for unlatching said latch to render the second dog operative, means controlled by the second stepper for energizing the reset relay, the reset relay being arranged to move said dogs to inoperative position, and means for returning both movable members to normal position.

17. A selector for automatic phonographs comprising a stepper, means for supplying a series of impulses to said stepper, a second stepper, means for supplying a series of impulses to said stepper, time delay means controlled by the first stepper for actuating the second stepper at an interval after the operation of the first stepper, and means controlled by the second stepper for rendering said time delay means inoperative.

18. A selector for automatic phonographs comprising a stepper, means for supplying a series of impulses to said stepper, a second stepper, means for supplying a series of impulses to said stepper, a condenser, means controlled by the first stepper for charging said condenser, an RC circuit connected to said condenser, means controlled by said circuit for supplying an impulse to the second stepper after a time delay, and means controlled by the second stepper for rendering said condenser and circuit inoperative.

19. A selector for automatic phonographs comprising a stepper, a second stepper, a condenser, means controlled by the first stepper for charging said condenser, voltage controlled impulse creating means normally connected to the first stepper, means controlled by the first stepper for connecting said impulse creating means to the second stepper, means controlled by the second stepper for connecting said impulse creating means to the first stepper, a time delay RC circuit normally connecting said condenser to the impulse creating means whereby said impulse creating means is actuated by the discharge of the condenser a definite time after the operation of the first stepper, and means controlled by the second stepper for discharging said condenser.

20. A selector for automatic phonographs comprising a stepper, a second stepper, a condenser, means controlled by the first stepper for charging said condenser, voltage controlled impulse creating means normally connected to the first stepper, means controlled by the first stepper for connecting said impulse creating means to the second stepper, means controlled by the second stepper for connecting said impulse creating means to the first stepper, a time delay RC circuit normally connecting said condenser to the impulse creating means whereby said impulse creating means is actuated by the discharge of the condenser a definite time after the operation of the first stepper, manually controlled means for operating said impulse creating means to create series of impulses, and means controlled by the second stepper for discharging said condenser.

21. A selector for automatic phonographs adapted to be operated by a pair of series of impulses, comprising a first stepper, a second stepper, a selector member controlled thereby, a reset relay, means normally supplying a series of impulses to the first stepper, means controlled by the first stepper for connecting the impulse supply means to the second stepper, a condenser arranged to be charged by the first stepper, time delay means controlled by the discharge of the condenser for actuating the second stepper, means controlled by the second stepper for first discharging and immediately thereafter charging said condenser, and means controlled by the reset relay for rendering said time delay means inoperative.
